UNITED STATES PATENT OFFICE

HEINRICH BERNHARD RÜDER, OF FRANKFORT-ON-THE-MAIN, GERMANY, ASSIGNOR TO
INTERNATIONAL PRECIPITATION COMPANY, OF LOS ANGELES, CALIFORNIA, A COR-
PORATION OF CALIFORNIA

COMBINED ELECTRICAL AND CENTRIFUGAL GAS CLEANING APPARATUS

Application filed September 5, 1930, Serial No. 479,997, and in Germany October 9, 1929.

- This invention relates to apparatus for removing suspended particles from gases by the combined action of electrical precipitation and centrifugal force, and particularly 5 to gas cleaning apparatus in which the gas is caused to whirl by passing the same between opposing walls arranged in spiral or circular fashion, and in which discharge electrodes are mounted in the space between said 10 walls and an electric discharge from said discharge electrodes is maintained so as to simultaneously subject the suspended particles to the action of centrifugal force and the action of the electric discharge.
- 15 The principal object of this invention is to provide an apparatus of the above type which will operate more efficiently than those heretofore used, and particularly an apparatus in which the optimum combination of 20 the two separating actions is obtained.

In previous apparatus of this type the electric discharge from the discharge electrodes has been directed in part outwardly toward the wall outside the whirling gases and in 25 part inwardly toward the wall inside the whirling gases, and the electric field in this latter direction has opposed the action of centrifugal force. The suspended particles contained in the portion of the gases between the 30 discharge electrodes and the outer wall have been precipitated outwardly both by centrifugal force and by electrical action, but the suspended particles in the portion of the gas between the discharge electrodes and the 35 inner wall have been subjected to the electric field tending to drive them toward the inner wall and to the action of centrifugal force tending to drive them away from said inner wall. Furthermore, since the centrifugal force concentrates the major portion of 40 the suspended particles in the outer portion of the gas stream, the inwardly directed electric discharge represents practically wasted energy.

45 An important object of this invention is to cause the electric discharge to occur principally between the discharge electrodes and the outer wall of the spiral gas passage, thus utilizing the energy of the electric discharge 50 to the best advantage. Not only is the elec-

tric discharge thus confined principally to the outer portion of the gas stream in which the concentration of the suspended particles is relatively high, but furthermore such electric discharge acts in the same direction as 55 the centrifugal force.

A further object is to permit the discharging surfaces of the discharge electrodes to be asymmetrically discharged in the spiral or curved gas passage and closer to the inner 60 wall thereof, thus bringing the major portion of the gas stream within the action of the outwardly directed electric discharge.

The apparatus of this invention comprises 65 essentially spaced curved wall members defining a spiral or curved path for flow of gas therebetween, means for causing whirling flow of gas in said curved passage, spaced discharge electrode members disposed in said passage, and a source of electric current connected to said wall members and to said discharge electrode members and adapted to 70 maintain an electric discharge from said discharge electrode members, said discharge electrode members having portions of relatively sharp surface curvature, such as points or edges, at their outer sides for facilitating electric discharge therefrom, and having 75 their inner sides of relatively gradual curvature and free from sharp points or edges, so as to minimize electric discharge from said inner sides, and said discharge electrodes being preferably mounted with the discharging portions thereof at a greater distance 80 from the wall outside the gas passage than from the wall inside the gas passage.

The accompanying drawings illustrate an apparatus embodying my invention, and referring thereto:

Fig. 1 is a side elevation of such apparatus.

Fig. 2 is a horizontal section on line 2-2 in Fig. 1.

The apparatus is shown as comprising wall members 1 curved about a substantially vertical axis and defining a spiral gas passage 2. The outermost wall provides a housing for the apparatus while the innermost wall encloses a central space 3 which communicates with the inner end of the spiral gas passage 100.

through opening 4 in said innermost wall. In the present case the gases are shown as delivered into the outer end of the spiral gas passage, by means of inlet flue 5 and connection 6, and withdrawn from the central space 3 by means of outlet flue 7, but it will be understood that the invention is not restricted as to the direction of gas flow through the spiral passage, and the inlet and outlet connections may be reversed if desired. The lower portions 1' of the walls converge downwardly and open into a collecting hopper 8 provided with any suitable means for removal of collected material.

15 Within the spiral gas passage, and intermediate the walls 1, are suspended a plurality of discharge electrode members 11. Said members are shown as connected at their upper and lower ends to spiral rods or pipes 20 12 and 13 respectively. The upper supporting rod 12 is shown as suspended by means of vertical rods or frame members 14 from transverse supporting bars 15 mounted on insulators 16. The frame members 14 are shown 25 as extending up through compartments 17 above the top wall of the apparatus, and are insulated by means of insulators 18 where they pass through the top walls of said compartments. The discharge electrode system 30 above described may be connected by an electrical conductor indicated diagrammatically at 19 to the high tension side of a source of electric current at suitable potential, while the walls 1, which constitute the collecting 35 electrodes, may be connected by a suitable conductor such as indicated diagrammatically at 21 to the low tension side of said source of current. Said collecting electrodes are also preferably electrically grounded as 40 indicated at 22. Said source of current may be of any suitable type adapted to produce either unidirectional or alternating electric current and to maintain a sufficient potential difference between the electrodes to effect 45 electric discharge therebetween. The current used may, for example, consist of unidirectional electric current produced by rectification of alternating current.

In accordance with this invention, the discharge electrode members 11 are shown as cylindrical or round in shape but provided with projecting fins or vanes 25 at one side, and are so mounted that the edges or points 50 of said fins or vanes are disposed at the outer sides of said discharge electrode members, thus providing portions of relatively sharp surface curvature disposed toward the wall outside the gas passage in which said discharge electrode members are mounted. 55 The inner sides of the discharge electrode members, on the other hand, are of relatively gradual curvature and free from sharp points or edges. Since electric discharge takes place much more easily from a sharp 60 edge or other element of relatively great sur-

face curvature than from a rounded surface of relatively small surface curvature, it is evident that there will be much less tendency for electric discharge from the discharge electrodes toward the inner wall than toward the outer wall. Consequently, the distance indicated at *a* from the sharp discharging edges 26 to the outer wall may be made greater than the distance *b* from such edges to the inner wall. 75

In operation, the gases enter the outer end of the spiral gas passage 2 and pass inwardly through said passage in vertical or whirling fashion, thus causing the suspended particles therein to be subjected to centrifugal action tending to force said particles outwardly with respect to the gas and toward the outer wall of said passage. Simultaneously, the suspended particles are also subjected to the precipitating action due to the 80 electric discharge and electrical field between the discharge electrodes and the collecting electrode surfaces. Since the discharge edges of the discharge electrodes are at a greater distance from the outer wall 85 than from the inner wall and also because of the greater tendency to outward discharge than to inward discharge, and furthermore, by reason of a greater concentration of suspended particles in the outer portion of the 90 gas stream by centrifugal action, the suspended particles will be acted upon to a much greater extent by the relatively strong electrical precipitating action directed outwardly from the discharge electrodes to the outer 95 wall than by the relatively weak electrical 100 precipitating action directed inwardly toward the inner wall. The apparatus, therefore, provides for maximum efficiency of utilization of the electrical energy in assisting 105 the action of centrifugal force tending to drive the suspended particles toward the outer wall. The suspended particles will thus be largely deposited upon the outer 110 wall of the spiral gas passage, although some deposition may also occur on the inner wall due to inwardly directed electrical precipitating action. Furthermore, some deposition may occur on the discharge electrode members themselves. The gas, freed 115 of a large proportion of the suspended material originally contained therein, finally enters the central space 3 whence it is removed through outlet flue 7. The deposited material falls between the converging wall 120 portions 1' into the collecting hopper 8, when it may be removed in any suitable manner.

I claim:

1. An apparatus for separating suspended material from gases comprising spaced 125 curved wall members defining a spiral gas passage, means for maintaining whirling flow of gas in said passage, spaced discharge electrode members disposed in said passage and insulated from said wall members, and 130

a source of electric current connected to said wall members and to said discharge electrode members and adapted to maintain an electric discharge from said discharge electrode members, said discharge electrode members having portions of relatively sharp surface curvature at their outer sides and having their inner sides of relatively gradual surface curvature and free from sharp dis-
5 charging edges.

10 2. An apparatus as set forth in claim 1, said discharge electrode members being mounted with said portions of relatively sharp surface curvature at a greater dis-
15 tance from the wall outside the gas passage than from the wall inside the gas passage.

In testimony whereof I have hereunto sub-
scribed my name this 21st day of August,
1930.
